United States Patent Office

Des. 229,385

Patented Nov. 27, 1973

229,385

PICTURE FRAME OR THE LIKE

Hugh N. Pace, 3516 Poole Road,
Raleigh, N.C. 27610

Filed Jan. 11, 1971, Ser. No. 105,766

Term of patent 14 years

Int. Cl. D6—06

U.S. Cl. D6—238

FIG. 1

FIG. 3

FIG. 1 is a front perspective view of a picture frame or the like showing my new design, the reverse side being a mirror image thereof,

FIG. 2 is an end perspective view; and

FIG. 3 is a bottom plan view.

I claim:

The ornamental design for a picture frame or the like, as shown and described.
